UNITED STATES PATENT OFFICE

PAUL MACHOWICZ, OF JAMAICA, NEW YORK

DESIGN FOR A DECORATIVE LAMP CASING

Application filed October 22, 1929. Serial No. 33,136. Term of patent 14 years.

To all whom it may concern:

Be it known that I, PAUL MACHOWICZ, a citizen of Poland, and a resident of Jamaica, borough of Queens, in the county of Queens and State of New York, have invented the new, original, and ornamental Design for a Decorative Lamp Casing, of which the following is a specification.

Reference is had to the accompanying drawing, in which—

I claim:

The ornamental design for a decorative lamp casing, substantially as shown.

PAUL MACHOWICZ.
